UNITED STATES PATENT OFFICE.

PLINY E. HOLT, OF STOCKTON, CALIFORNIA.

RADIATOR.

1,124,740.

Specification of Letters Patent.

Patented Jan. 12, 1915.

Application filed October 14, 1911. Serial No. 654,737.

To all whom it may concern:

Be it known that I, PLINY E. HOLT, a citizen of the United States, and residing at 820 West Poplar street, in the city of 5 Stockton, county of San Joaquin, and State of California, have invented certain new and useful Improvements in Radiators; and I do hereby declare the following to be a full, clear, and exact description of the said invention, such as will enable others skilled in the art to which it most nearly appertains to make, use, and practise the same.

This invention relates to improvements in radiators, and consists of the novel construction and arrangement of the parts.

The objects sought to be accomplished are the production of a radiator particularly adapted to the cooling of the circulating medium of internal combustion engines; where- 20 in it is necessary to guard against leakage incidental to the rapid expansion and contraction of the parts of the radiator; and to arrange these parts in sections which can readily be removed and replaced.

25 With these objects in view, the invention broadly stated consists of an upper and lower header, having manifolds slidably connected therewith; radiation tubes with their ends fixed in these respective mani- 30 folds; whereby the heated water from the circulating system discharged into the top header, passes through the manifolds, down through the radiation tubes, wherein it is subjected to a fan blast which facilitates the 35 radiation of heat, thence through the lower manifolds into the lower header, from whence it is pumped back into the radiating system.

In the drawings; Figure —1— is a front 40 elevation illustrating a radiator constructed in accordance with this invention. The top header is shown partially in cross section to disclose the arrangement of the distribution plates therein. Figs. 2 and 3 are detail 45 sectional views illustrating the upper and lower headers, respectively. Fig. 4 is a front elevation of one of the manifolds.

In detail the construction consists of the upper header 1, into which the water or cir- 50 culating medium is pumped. The water is introduced into the header 1 through the opening 2, below which it impinges upon and is divided by the apex of the distribution plate 3, down which it travels in oppo- 55 site directions, until it falls upon and is divided by the apex of the distribution

plates 4 and 5, down which it travels in opposite directions, until it is again divided by the distribution plates 6 and 7. These distribution plates are preferably cast integral 60 with the header and located as disclosed in the drawings. Their particular function is to cause an equal distribution of the incoming liquid to the radiation tubes, particularly when the radiator is not plumb as 65 often occurs in automobile or tractor practice.

The lower header 8 is similar to the upper, with the exception of the distributing plates, which are absent. Both headers are 70 provided with the openings 9, surrounded on the outsides by an embossment adapted to be planed off, to provide a suitable surface for the gaskets 10. The number of these openings is multiplied according to 75 the width of radiator desired.

The manifolds 11 each consist of a hollow casting, with an enlarged inlet suitably finished to bear against the gasket 10, coincident with the opening 9. Pressure is 80 brought to bear between the headers and the manifolds, pressing the gasket therebetween, by the bolts 12. In the rear of the headers the sockets 13 are provided into which the head of the bolt is introduced with the gas- 85 ket 14 and washer 15 interposed between the bottom of the socket and the head of the bolt. The threaded end of the bolt extends through the stuffing box 16 provided in the front end of the manifold and is drawn up 90 by the nut 17. The body 18 of the bolt can be flattened or attenuated to allow for a limited displacement of the manifold with the header without disturbing the packing of the head of the bolt, or the stuffing box 95 where the bolt passes through the header or the manifold. The further advantage of this attenuation is disclosed later.

The lower manifolds engage the header 8 in exactly the same manner as just described. The upper and lower manifolds are rigidly joined and connected by the interposed series of radiation tubes 19, the ends of which are soldered or otherwise fixed in the manifolds. The radiating sur- 100 face of the tubes is increased by the addition of the spiral fin 20. This particular construction of radiation tube is a stock product. It is obvious that other forms of radiation tubing is equally applicable in 105 the construction of this invention. The upper and lower manifolds rigidly joined by

the radiation tubes as described, comprise a complete unit readily removable from the headers by the simple unscrewing of the nut 17. Should a leak develop in any of the 5 series of tubes, the whole section can be removed and a perfect one substituted in a few moments, and the injured section repaired at leisure; or the damaged section can be removed and the openings 9 closed 10 by blind plates as circumstances require.

In the practice of this art, it is usual to increase the radiation power of the tubes by a blast from a mechanically driven fan. Since the efficiency of a fan decreases 15 toward the center, the outer tubes often cool and contract faster than those in the influence of the center of the fan blast: or other conditions may be present which would cause an unequal expansion or con- 20 traction of the tubes or other parts of the radiator. In automobile or tractor service vibration and mechanical twisting, and other displacements are to be overcome in the radiator to prevent leakage. The elastic 25 gasket 10 interposed between the headers and the manifolds, hermetically seal the joint by compression, while their elasticity admit of the necessary, though slight dislocation of the headers and manifolds, due 30 to expansion, contraction or other mechanical forces to be counteracted. If one side of the gasket is coated with graphite or other suitable antifriction compound, the manifolds can be forced out of coincidence 35 with the openings 9 to a surprising extent, without causing leakage; it is under these extreme circumstances that the flexibility of the bolts perform the desired function in an obvious manner.

40 The upper and lower headers are joined by uprights 21 of channel section to which the headers are bolted through the lugs 22. In this manner the same headers can be made to serve for radiators of greater or 45 less capacity, by varying their height.

The headers are provided with the cleaning plugs 23, the lower being also provided with the drainage cock 24.

This form of radiator is adaptable to the 50 various forms of circulating systems, whether the circulation be natural thermosiphon, or force pump circulation, by suitable changes in the headers.

Having thus described this invention, what is claimed and desired to secure by 55 Letters Patent is:

1. A radiator including an upper and a lower header each having a depressed seat formed in the outer side face thereof and having an opening formed in the opposite side thereof, a gasket in each seat and a gasket surrounding the opening, tube connected manifolds abutting the gaskets which surround said openings and having stuffing boxes on the free outer sides thereof, and bolts passed through the headers, manifolds and stuffing boxes and having heads which engage the first named gaskets and having nuts which engage the stuffing boxes, said bolts having central portions which are thinned so as to allow movement of the tubes and manifolds.

2. A radiator including an upper and a lower header, a series of spaced independent manifolds engaged with each header, tubes connecting the respective upper and lower manifolds, and a bolt passed completely through each manifold and through the header which engages the manifold whereby the nuts of the bolts and the bolt heads are 80 exposed and accessible from the exteriors of the headers and manifolds, said bolts having thin central parts which flexibly connect the bolt ends and which aline with the joints formed between the headers and manifolds.

3. A radiator including an upper and a lower header, a manifold engaged with each header, tubes connecting the manifolds, bolts passed completely through the manifolds and headers, sealing means between the bolt heads and the headers, sealing means between the nuts and the manifolds and sealing means between the headers and manifolds, said bolts having thin central 95 portions which connect the bolt ends whereby the bolt ends may remain relatively stationary to the manifolds and headers and the manifolds be permitted to have movement relative to the headers.

In testimony whereof, I have hereunto set my hand this 13th day of September 1911.

PLINY E. HOLT.
